UNITED STATES PATENT OFFICE.

ROWLAND HILL, OF CINCINNATI, OHIO.

ROOF-FRAMING SQUARE.

1,241,976.

Specification of Letters Patent.

Patented Oct. 2, 1917.

Application filed December 11, 1915. Serial No. 66,305.

To all whom it may concern:

Be it known that I, ROWLAND HILL, a citizen of the United States of America, residing at Cincinnati, in the county of Hamilton 5 and State of Ohio, have invented certain new and useful Improvements in Roof-Framing Squares, of which the following is a specification.

The invention relates to a framing square, 10 and more particularly to the class of roof framing squares, for use by carpenters, mechanics, or any other persons.

The primary object of the invention is the provision of a square of this character, 15 wherein the work of framing a roof is materially simplified by the use of the square, and any person unskilled in this particular art can readily and conveniently accomplish the work with success.

20 Another object of the invention is the provision of a square of this character, wherein the obverse and reverse sides thereof are marked or otherwise with scales, which permits the use of an ordinary bevel

25 square for ascertaining with accuracy the side cut of hip and valley rafters, plumb-cuts, side bevels and pitch of hip, jack, cripple and common rafters, and the length per foot for the hip, valley, and common and 30 jack rafters, for the framing of a roof with despatch.

A further object of the invention is the provision of a square of this character, which is extremely simple in construction, 35 thoroughly reliable and efficient in its purpose, capable of being placed upon any straight edge tool, strong, durable, and inexpensive in manufacture.

With these and other objects in view, the 40 invention consists in the features of construction, combination and arrangement of parts as will be hereinafter fully described, illustrated in the accompanying drawings, and pointed out in the claim hereunto ap- 45 pended.

In the accompanying drawings:

Figure 1, is a side elevation of a square constructed in accordance with the invention.

50 Fig. 2, is a view similar to Fig. 1, looking toward the opposite side.

Similar reference characters indicate corresponding parts throughout the several views in the drawings.

55 Referring to the drawings, in detail, the square comprises a body A, preferably made

from steel, although it may be made from any other rigid and durable material, having long and short limbs or arms 5 and 6, respectively, arranged at right angles to each other. Marked by stamping or etching on opposite faces of the body A, at the outer and inner edges of both limbs or arms 5 and 6, thereof are longitudinally disposed scales, as at B, the scales at the outer edge of the 65 longer limb or arm 5, having a range from 1 to 16 inches, and it is marked accordingly, although this limb or arm can be of any desired length with a scale corresponding thereto, while the scales at the inner edge 70 of the longer limb or arm range from 1 to 14 inches, and it is marked accordingly.

The scales on the outer edge of the shorter limb or arm 6, have a range of from 1 to 12, 75 inches, and it is marked accordingly, while the scales at the inner edge of this limb or arm range from 1 to 10, inches, and it is marked accordingly, yet this limb or arm can be of any other desirable length, should the occasion require.

80 Within the space between the scales on one side and at the inner and outer edges of the shorter limb or arm 6, are spaced diagonally disposed marks or lines 7, indicative of backing bevels for hips and valleys, having 85 pitch range from 3 to 12 inches, while on the same face of said limb or arm and in the space between the outer and inner scales of the longer limb or arm 5, are angularly disposed marks or lines 8, indicative pitch, 90 plumb-cuts, side bevels and length per foot run for hips and valley rafters.

Within the space between the scales on the other side and at the inner and outer edges of the shorter limb or arm 6, are digits 95 and fractions thereof, as at 9, indicative of the difference in length of jack and cripple rafters, while on the same face of the body between the scales on the longer limb or arm 5, are angularly or diagonally disposed 100 marks or lines 10, indicative of plumb-cuts, bevels and length per foot run for common and jack rafters.

What is claimed:

A square having a long and a short arm, 105 the outer edge of the longer arm being calibrated to measure off 16 inches while the outer edge of the shorter arm is calibrated to measure off 12 inches, said inches being designated upon said square and run in opposite directions from the outer corner thereof, each side of the square being simi- 110

larly calibrated into inches and similarly designated, one side of the longer arm of said square being inscribed with a series of diagonal lines terminating at the graduations 5 designated 3 to 12 inclusive, said last-named arm being also inscribed with a designated series of values opposite same representing the length per foot run of jack rafters, etc., the other side of the longer arm of said square 10 having a similar series of diagonal lines inscribed thereupon also joining the numeral 3 to 12 and having opposite the same a designated series of values representing the plumb cuts of ribs and valleys, etc., and of 15 the diagonal lines on the first mentioned

side of the long arm of said square representing the hypotenuse of a triangle having a 12 inch leg and a base of as many inches as is designated by the inch numeral opposite this line, while any of the diagonal lines 20 on the opposite side of said arm represent the hypotenuse of a triangle whose leg is 16 inches long.

In testimony whereof I affix my signature in the presence of two witnesses.

ROWLAND HILL.
